(57) **CLAIM**

The ornamental design for a terminal block, as shown and described.

DESCRIPTION

FIG. 1 is a front perspective view, portions being shown in broken lines, of the terminal block showing my new design; FIG. 2 is a front view, portions being shown in broken lines, of the terminal block of FIG. 1;

FIG. 3 is a bottom plan view, portions being shown in broken lines, of the terminal block of FIG. 1;

FIG. 4 is a left side view, portions being shown in broken lines, of the terminal block of FIG. 1;

FIG. 5 is a right side view, portions being shown in broken lines, of the terminal block of FIG. 1;

FIG. 6 is a top plan view, portions being shown in broken lines, of the terminal block of FIG. 1; and,

FIG. 7 is a rear view, portions being shown in broken lines, of the terminal block of FIG. 1.

The portions shown in broken lines form no part of the claimed design.
